UNITED STATES PATENT OFFICE

152,378

DESIGN FOR A FLAG HOLDER

Claiborne Adams Skinner, Webster Groves, Mo.

Application October 20, 1947, Serial No. 142,011

Term of patent 14 years

(Cl. D29—17)

To all whom it may concern:

Be it known that I, Claiborne Adams Skinner, a citizen of the United States and a resident of Webster Groves in the county of St. Louis and State of Missouri, have invented a new, original, and ornamental Design for a Flag Holder, of which the following is a specification, reference being had to the accompanying drawing, forming part thereof.

Fig. 1 is a perspective view of a flag holder, showing my new design, the essential features being shown in full lines, the flag being shown for illustrative purposes only.

Fig. 2 is a front elevational view,

Fig. 3 is a side elevational view,

Fig. 4 is a rear elevational view; and
Fig. 5 is a top plan view.

I claim:

The ornamental design for a flag holder, substantially as shown and described.

CLAIBORNE ADAMS SKINNER.
